UNITED STATES PATENT OFFICE.

JOHN ELDERKIN, OF ROCHESTER, NEW YORK.

DESIGN FOR A SHOE.

SPECIFICATION forming part of Design No. 17,705, dated September 13, 1887.

Application filed June 22, 1887. Serial No. 242,129. Term of patent 14 years.

To all whom it may concern:

Be it known that I, JOHN ELDERKIN, of Rochester, in the county of Monroe and State of New York, have invented and produced a new and original Design for Shoes, of which the following is a specification, reference being had to the accompanying drawings, forming a part thereof.

In said drawings, Figure 1 is a perspective view of a shoe embodying my design. Fig. 2 is a side view of the same.

The leading or striking feature of my design will be seen to lie in the peculiar configuration of the seam uniting the vamp and quarters. This seam, after it leaves the point E at the side of the shoe, curves slightly outward to the point A, thence inward until the point B is reached, when a somewhat abrupt turn is made, the seam extending thence straight forward, or forward and slightly outward, until the point C is reached, when it again turns and passes straight over the forward portion of the vamp and continues in like manner on that side of the shoe. The bottom of the last scallop of the button-fly is curved to conform to the contour of that portion of the seam lying between the points A and B, so as to preserve the symmetry of the design.

The quarters of a shoe having a seam such as just described appear, when viewed from a point directly in front, to be wide at the

points A, narrowing in rapidly to B, then curving slightly outward to C, when the seams on either side turn and unite at the center line of the shoe, thus forming an extension or tongue extending forward of the button-fly, slightly wider at the forward end than at the base, the latter effect being produced in a measure by the bulging or raising of the leather at the instep for the accommodation of the wearer's foot. The edges of the quarters overlie the vamp and are rounded or beaded, as will be readily understood.

I claim—

1. The design for a shoe herein described and shown, consisting in the ornamental seam extending straight across the fore portion of the vamp to rounded corners or points C, thence backward and slightly inward, thence outward in concave curves B, as set forth. 50

2. The design for a shoe herein described and shown, consisting in the ornamental seam curved after leaving the sole on either side inward in concave curves E, thence outward to points A, thence inward in concave curves B, 55 extending forward and slightly outward to rounded points C, and then straight across the fore portion of the vamp, as set forth.

JOHN ELDERKIN.
